UNITED STATES PATENT OFFICE.

CLYDE S. WRIGHT, OF TOLEDO, OHIO, ASSIGNOR TO THE NATIONAL SUPPLY COMPANY,
OF TOLEDO, OHIO, A CORPORATION OF OHIO.

UNDERREAMER.

1,242,508.

Specification of Letters Patent.

Patented Oct. 9, 1917.

Application filed October 24, 1916. Serial No. 127,842.

To all whom it may concern:

Be it known that I, CLYDE S. WRIGHT, a citizen of the United States, residing at Toledo, in the county of Lucas and State of Ohio, have invented new and useful Improvements in Underreamers, of which the following is a specification.

My invention relates to underreamers and its object is to provide an underreamer which shall have a very simple construction whereby the cost may be kept low and the parts are not liable to get out of order.

Referring to the accompanying drawings, Figure 1 is a side elevation of an underreamer constructed in accordance with the principles of my invention, a portion being broken away; Fig. 2, a vertical section of the underreamer with the bits expanded, the upper part of the underreamer and the well 10 casing being broken away; Fig. 3, a section similar to Fig. 2 but showing the bits collapsed; and Fig. 4, a bottom plan view of Fig. 2. Figs. 5 to 9 are sections of Fig. 2 on the lines V—V to IX—IX, respectively.

On the drawings, 1 represents the elongated cylindrical body of my underreamer having the threaded upper end 2 for connecting the body to a line of drill-rods, not shown. The body 1 has the axial or central opening 3 preferably closed at its upper end and communicating at the lower end with the bit-receiving chamber which comprises three portions, namely, the upper preferably annular portion 4 having a larger diameter than the diameter of the opening 3 above the same, the large lower preferably cylindrical portion 5 extending to the bottom of the body 1, and the intermediate portion 6 between the portions 4 and 5, its diameter being smaller than that of either of the other portions.

7 is a collar seated in the lower end of the opening 3 just above the portion 4 of the bit-receiving chamber, and is secured there-in by means of the pin 8 which extends through the body 1 and a portion of the annular groove 10 in the collar.

11 is a rod reciprocable in the opening 3, the collar 7 and the said chamber, and has its upper end screwed into the slotted nut 12 reciprocable in the upper end of the opening 3. An expansion spring 13 sur-

rounds the rod 11 and bears at one end against the under side of the slotted nut 12 and at the other end against the upper side 55 of the collar 7.

The portion of the body 1, a short distance above the collar 7, is provided with diametrically opposite slots 14 extending from the periphery of the body entirely 60 through to the opening 3. The slots 14 are widened near their upper ends as shown at 15. I provide each slot 14 with an elbow lever 16, one member 17 of each lever extending transversely of the body 1 to the 65 center of the opening 3 and to the middle of the slot 18 in the upper end of the slotted nut 12. The other members of the elbow levers 16 lie lengthwise in the slots 14 and have their lower ends provided with the 70 heads 19 which are somewhat wider than the slots 14. The body is provided with the recesses 20 to receive the heads 19 which when they are in the recesses have their upper faces substantially flush with the 75 periphery of the body 1. The upper ends of the recesses 20 are beveled outwardly and upwardly to correspond with bevels on the upper ends of the heads 19 to facilitate the movement of the heads into and from the 80 recesses. The transverse members of the elbow levers are somewhat thickened to provide heads or bearings 21. These heads or bearings are adapted to be passed through the widened portions of the slots 14 and 85 into the opening 3. These heads or bearings, being somewhat larger than the width of the slots 14, prevent the lever 16 from moving outwardly through the slots 14 when the heads of bearings are above or below 90 the said widened portions 15 of the slots 14. The opposing ends of the transverse members of the levers 16 are beveled upwardly and outwardly so that when the levers have their heads 19 in the recesses 20, 95 there is a wedge-shaped opening between the said opposing ends of the levers, and so that the levers may swing outwardly from the position shown on Fig. 3 to that shown on Fig. 2.

I provide a pair of bits 22 having the same construction. Each bit has at its upper end an outwardly extending flange 23 which extends into the recesses constituting

the upper portion 4 of the bit-receiving chamber. Each bit has also the portion 24 which is adapted to fit against the wall of the bottom portion 5 of the said chamber when the bits are in their expanded, or most widely separated, position. The portions 25 of the bits lie between the portions 23 and 24 and rest against the walls of the intermediate portion 6 of the said chamber when the bits are most widely expanded. The bits have below the portions 24 the portions 26 provided at their upper ends with the shoulders 27 lying immediately below the lower end of the body 1. The outer surfaces of the portions 26 of the bits extend slightly beyond the periphery of the body 1 when the bits are most widely expanded, the outer surfaces of the portions 26 being inclined downwardly and outwardly to the cutting edges 28. When the bits are in their expanded position, shoulders 27 abut against the lower end of the body 1, and the upper ends of the portions 24 of the bits abut against the upper wall of the portion 5 of the bit-receiving chamber. When the bits are in their collapsed position, as shown on Fig. 3 they are supported by the flanges 23 which rest on the lower wall of the upper portion 4 of the said chamber.

It will be noticed from Fig. 2 that, when the bits are in their expanded position, their opposing edges are separated at some distance from each other and it will be noticed from Fig. 3 that when the bits are in their collapsed position, the lower portions of the bits lie close together and that the outer faces of the bits lie within the periphery of the body 1 and substantially parallel therewith. It thus appears that the flanges 23 act as suspending means for the bits.

The rod 11 extends down between the bits 26 which lie so close to the said rod as to prevent the upper ends of the bits from moving inwardly toward each other, thereby preventing their dropping down through the body of the underreamer. It will be seen from Fig. 3 that even when the bits are collapsed, the upper ends thereof are separated by a space, at least, equal to the distance the flanges 23 extend outwardly beyond the portions 25 of the bits, so that when the rod 11 is withdrawn from the underreamer the upper end of one bit may be moved toward the other bit and then withdrawn downwardly through the bit-receiving chamber. When one bit has been removed the other bit can be removed in a similar manner.

The lower end of the rod 11 is provided with a bit-separating head 30 which, when the spring 13 is allowed to expand, is drawn up between the bits as shown in Fig. 2. This head has its sides beveled to correspond with inclined coöperating portions of the bits. The head 30 has at its upper end wedge-

shaped lugs 31 which are adapted to enter between the meeting faces of the collapsed bits and move them apart at their lower ends. The opposing walls of the bits are provided with transverse shoulders 32 and the head 30 is provided with correspondingly shaped shoulders which bear against the shoulders 32 when the head 30 is in its uppermost position. The sides of the head 30 both above and below its said shoulders are tapered upwardly toward each other so that when the head 30 moves upwardly it will force the bits outwardly to their fully expanded position where they are securely held by the sides of the head 30. The bottom of the head 30 is provided with an elongated recess 33 to receive the lugs on the lower end of the rod 11, the pin 37 passing through the lower end of the head 30 and the rod 11, whereby the said head is securely held on the rod.

I provide diametrically opposite lugs 35 which extend through the body 1 and into slots 36 in the portions 24 of the bits in order to prevent the bits from accidental rotation in the body, since if they were free to rotate it might cause the rod 11 to be screwed out of the slotted nut 12.

The parts being as shown in Fig. 3, in which the bits are shown collapsed and the heads 19 of the levers 16 are shown in the recesses 20, the underreamer is pushed down into the well-casing or drill-pipe 36^a. The size of the underreamer and of the casing or drill-pipe 36^a should be such as to prevent the levers 16 from moving laterally out of the slots 14 sufficiently to allow the heads 19 to escape from the recesses 20, for if the said heads 19 should escape out of the recesses 20, the spring 13 would draw the bit-separating head 30 upwardly and cause the cutting edges of the bits to be expanded against the casing or tube 36^a and interfere with the downward movement of the underreamer.

When the underreamer has been pushed below the lower end of the casing or pipe 36^a, the spring 13 at once causes the levers 16 to be swung outwardly, thereby freeing the heads 19 from the recesses 20. The slotted nut 12, the levers 16, the rod 11 and the bit-separating head 30 are all moved upwardly by the spring 13 and the bits 22 are moved to their expanded position as shown in Fig. 2.

When the underreamer is drawn upwardly from its position shown in Fig. 2, the heads 19 engage with the lower end of the casing or tubing 36^a and prevent the upward movement of the levers 16, the slotted nut 12, the rod 11, and the bit-separating head 30, while the body 1, the collar 7, and the bits 22 continue their upward movement. As soon as the recesses 20 come opposite the said heads 19, the latter are forced inwardly

into the said recesses to the position shown on Fig. 3 at which time the bits will be raised above the separating head 30 and caused to assume their collapsed position.

5 In case the drive shoe on the lower end of the well-casing becomes distorted or elliptical, one of the levers 16 is sure to operate, thus allowing the bits to collapse so that the underreamer can pass up through the casing. If only one lever be used it might be possible for the underreamer to pass partially up through a distorted or elliptical shoe without the lever being operated so as to lower the head 30 10 and allow the bits to collapse. In such a case the underreamer might by reason of the expanded condition of the bits become so wedged in the shoe that it would be very difficult, if not impossible, to get the underreamer out of the well. Each lever 16 can work independently so that if one breaks or fails to work the remaining one might still operate to release the bits.

I claim—

25 1. In an underreamer, an elongated body having a central bore communicating at its lower end with a bit-receiving chamber, having lateral recesses at its upper end and a relatively large portion at its lower end, 30 bits having at their upper ends lateral flanges in the recesses and at their lower ends cutting edges, the bits being suspended on the said flanges, and adapted to swing in the larger portion of the chamber, a reciprocable rod situated in the bore and between the bits, a bit-separating head on the lower end of the rod, and means for holding the rod in one position to separate the bits and in another position to allow the bits to collapse.

40 2. In an underreamer, a centrally bored body, bits connected to the lower portion thereof so as to have free oscillating motion, a reciprocable rod arranged between the bits 45 and in the bore in the body, a bit separating head on the lower end of the rod arranged to separate the bits when the rod is in its upper position, a slotted device on the rod, an elbow lever having one arm extending 50 through the body and into the slot in the said device and having the other arm extending toward the bottom of the body, yielding means for moving the rod upwardly and holding the same in its upper 55 position, and means on the lever, adapted for engagement with the interior of a pipe, for retaining the rod in its lower position.

3. In an underreamer, a centrally bored body, bits connected to the lower portion thereof so as to have free oscillating motion, a reciprocable rod arranged between the bits and in the bore in the body, a bit separating head on the lower end of the rod arranged to separate the bits when the rod is in its 60 upper position, a slotted device on the upper

end of the rod, an elbow lever having one arm extending through a longitudinal slot in the body and into the slot in the said device and having the other arm lying in the said longitudinal slot and extending toward the bottom of the body, yielding means for moving the rod upwardly and holding the same in its upper position, and means on the lever, adapted for engagement with the interior of a pipe, for retaining the rod 70 in its lower position, the said means including a head on the lever arranged to enter a recess in the body when the rod is in its lower position.

4. In an underreamer, a centrally bored 80 body having a relatively large chamber at its lower end, the upper portion of the chamber having lateral recesses, bits in the chamber having portions at their upper ends projecting into the recesses and supporting 85 the bits so that they may have free oscillating motion, a rod reciprocable between the bits and in the bore in the body, and a bit-separating head on the rod adapted to expand the bits in the chamber when the rod 90 is moved upwardly and to allow them to collapse when at its lowest position, the relative cross-section of the rod and bits being such as to allow the bits to swing toward each other at their lower ends when the 95 rod is lowered and to prevent the upper ends of the bits moving toward each other so as to permit the bits to escape from the recesses.

5. In an underreamer, a centrally bored 100 body, bits connected to the lower portion thereof so as to have free oscillating motion, a reciprocable rod arranged between the bits and in the bore in the body, a bit separating head on the lower end of the rod arranged 105 to separate bits when the rod is in its upper position, a slotted device on the rod, an elbow lever having one arm extending through a longitudinal slot in the body and into the slot in the said device and having 110 the other arm lying in the said longitudinal slot, yielding means for moving the rod upwardly and holding the same in its upper position, and means on the lever, adapted for engagement with the interior of a pipe, 115 for retaining the rod in its lower position.

6. In an underreamer, a centrally bored body, having a lateral slot with a widened portion communicating with the central bore, bits supported by the lower end of 120 the body, a rod reciprocable in the bore, a bit-separating head on the rod, a spring tending to move the rod upwardly, and an elbow lever having one end lying lengthwise of the body and the other end extending through the lateral slot and urged upwardly by the rod, the last named end of the lever having a widened portion insertible through the widened portion of the slot, whereby, when the widened portion of the 130

lever enters the bore and moves lengthwise thereof, the lever is retained in the lateral slot.

7. In an underreamer, a centrally bored body having a chamber in its lower end, the upper end of the chamber having a recess, bits suspended on the bottom wall of the recess, a rod reciprocable in the bore and

having a nut thereon, means preventing the nut from turning, a bit-wedging device on the rod non-rotatable with respect to the bits, and means preventing the bits rotating in the body.

Signed at Toledo, Ohio, this 20th day of October, 1916.

CLYDE S. WRIGHT.
